UNITED STATES PATENT OFFICE.

FERDINAND W. KROGH, OF SAN FRANCISCO, CALIFORNIA.

CENTRIFUGAL PUMP.

1,163,242.

Specification of Letters Patent.

Patented Dec. 7, 1915.

Application filed July 17, 1913. Serial No. 779,410.

To all whom it may concern:

Be it known that I, FERDINAND W. KROGH, of San Francisco, California, have invented certain new and useful Improvements in 5 Centrifugal Pumps, whereof the following is a specification.

This invention relates to centrifugal pumps, not only those that are used for deep well pumping, but also contractors' pumps, 10 such as are used for keeping a place dry while work is progressing and also relates to certain features disclosed in my application filed Jan. 6, 1913, Serial No. 740,299.

The objects of the invention include; the 15 balancing of the impeller; the easy removability and replacement of all parts subject to wear and the prevention of tools or other objects which may accidentally fall into the discharge from entering the body of the 20 pump where they might cause damage.

To these ends the invention comprises a pump casing provided with a suction and a discharge, an impeller mounted therein and by its rotation causing the water to enter 25 at the suction and pass out of the discharge; a chamber at the upper part of the impeller, closed by a diaphragm in the casing above the impeller, whereby leakage from the discharge entering said chamber causes a pressure 30 therein and pushes the impeller toward the suction; ports in the diaphragm connect with a space above the same from which openings connect with the outside of the casing so that the water may be thrown through said 35 ports and space and into the body of water outside the pump; a chamber beneath the impeller surrounding the suction thereof, and connected with the discharge, whereby the pressure of the column of water in the 40 discharge opposes the suction; a grating in the discharge above the body of the pump; the making of said diaphragm and other parts easily removable; and including a removable bushing at the suction orifice, 45 whereby the parts subject to wear are easily replaced.

In the accompanying two sheets of drawing, I have shown my invention as applied to a single unit pump, it being understood 50 that it may be equally applied to tandem pumps in which the several units may be identical with the one shown or otherwise.

In the drawings:—Figure 1 is a sectional elevation through the center of the pump.

Fig. 2 is a top view of the casing showing 55 the grating, and Fig. 3 is an inverted section taken at the line *a*, *a* of Fig. 1.

In these figures: 1 represents the body of a pump connected by the flange joints 2, with a discharge 3, and provided with a suction 60 4 connected to it by the flange joint at 5. The pump may also be provided with a suction pipe 6, secured to it by the flange joint 7 when desired.

8 is the impeller mounted upon the shaft 65 9, and sharpened toward the suction end, as shown, to reduce the resistance of the inflowing water.

10 are the usual impeller arms, which need not be further described.

Under the impeller is a chamber 11 surrounding the suction and connecting with the discharge portion of the casing at 12, whereby the pressure of the water in the discharge acts upon the under side of the impeller, and tends to push it up away from 75 the suction.

The impeller includes a downward extending annular flange 13 forming the throat thereof, which partly enters into the suction 80 orifice and forms a connection therewith at all times in the movement of the impeller. Surrounding this flange 13 is a bushing 14, provided with a flange portion 15, by which it may be secured to the casing 4. The upper part of the impeller includes a longitudinal flange 16, and an inward extending transverse flange 17, which parts form a chamber 18 in the upper part of the impeller. 90

19 represents the bearing for the shaft 9 in the casing. At the lower edge of the bearing 19 there is a diaphragm 20, provided with a downward extending flange 21 at its periphery which embraces the flange 16 95 of the impeller. These parts are secured to the casing in a suitable manner at a point 22. Near the outer edge of the diaphragm 20 are ports 23 which are closed by the flange 17 when the impeller is in the position shown in Fig. 1. When, however, the impeller moves toward the suction the ports 23 are opened and water in the chamber 18 is driven through them by centrifugal force into the space 24 in the casing, whence it 105 passes by the channels 25 to the outside of the pump.

26 represents a grating made of wire cloth,

or of other suitable construction, which protects the interior of the pump from any objects which may fall into the discharge at any time.

- 5 The operation of my pump is as follows: The rotation of the impeller draws the water in through suction 6, and forces it out through the discharge 3. The suction, together with the weight of the impeller and shaft, etc., tends to draw the impeller downward, till the shoulder at 27 contacts the top of bushing 14. To offset these forces, the pressure of the water in the chamber 11, due to the hydrostatic head in the discharge, 10 tends to force the impeller up away from the suction, and into the position shown in Fig. 1. While in this position, the leakage of water through the joints between the impeller and the diaphragm 20, and its flange 21, produces a pressure in the chamber 18, and against the under side of the diaphragm 20, and tends to push the impeller away from the diaphragm. Such movement of the impeller opens the ports 23, and the 15 water in chamber 18 is thrown out by the centrifugal force, engendered by the rotation of the impeller, into the space 24, and thence through the channels 25, to the outside of the casing. 20 It will be observed that the parts subject to wear, aside from the journals and bearings of the shaft, are the impeller; the diaphragm 20; the flange 21; and the bushing 14. These parts are all easily gotten at for 25 repair, or for removal and replacement, by simply disconnecting the joints at 2 and 5.

The above pump may be used by itself or as a member of a tandem, or series of pumps, and in the latter case it may be the initial 40 pump of the series or tandem, or one of the other pumps thereof.

Having thus described my invention and believing I have produced useful and novel improvements in the art to which it appertains, let it be understood that I do not wish to be limited to the exact construction and arrangement of the several parts composing the same, as many changes can be made without departing from the spirit thereof, 45 but

What I claim and desire to secure by United States Letters-Patent is:

1. A centrifugal pump comprising a casting having a chamber, a self balancing impeller provided with a chamber in its upper part, registering with said casing chamber, and a removable diaphragm between said chambers provided with a port adapted to be opened and closed by the axial movement 55 of said impeller.

2. A centrifugal pump comprising a casting having a chamber, a self balancing impeller provided with a chamber in its upper part opposite said casing chamber, and a 60 diaphragm having ports near its periphery

adapted to open and close communication between said chambers by the axial movement of said impeller.

3. A centrifugal pump including a casing, having an upper chamber therein, closed by a removable diaphragm, downwardly projecting ports from said diaphragm communicating with a pressure chamber formed in the impeller of the pump, an annular shoulder in said impeller surrounding said pressure chamber adapted to close said ports and flanges on said diaphragm and said impeller coöperating to partially seal said chamber in the impeller. 70

4. A centrifugal pump comprising a casing, a self-balancing impeller provided with a pressure chamber, a removable diaphragm, secured to said casing, adapted to close said pressure chamber and a downward projecting annular flange on said diaphragm 75 engaging the upper part of said impeller and forming therebetween a running joint. 80

5. A centrifugal pump comprising a casing, a self-balancing impeller, a removable diaphragm applied to the casing and constituting with the impeller, a pressure chamber and a removable running joint. 90

6. A centrifugal pump including a casing having an upper chamber therein closed by a removable diaphragm having a plurality 95 of openings, a flange on the impeller of the pump adapted to close said openings, flanges on said impeller and said diaphragm, co-operating to form a pressure chamber in said impeller. 100

7. A centrifugal pump including a casing having an upper chamber formed therein closed by a removable diaphragm, downwardly projecting ports from said diaphragm communicating with a pressure chamber formed in the impeller of the pump, an annular shoulder on said impeller adapted to close said ports, flanges on said diaphragm and said impeller, coöperating to partially seal said chamber in the impeller, 105 a throat on said impeller, a suction opening in said casing surrounding said throat and a removable bushing interposed between said throat and said suction opening. 110

8. A centrifugal pump including a casing, having an upper chamber therein, closed by a removable diaphragm, ports in said diaphragm communicating with a pressure chamber formed in the impeller of the pump, a flange in said impeller adapted to close said ports, and flanges on said diaphragm and said impeller coöperating to partially seal said chamber in the impeller. 115

9. A centrifugal pump including a casing having an upper chamber formed therein closed by a removable diaphragm, ports in said diaphragm communicating with a pressure chamber formed in the impeller of the pump, a flange on said impeller adapted to close said ports, flanges on said diaphragm

and said impeller, coöperating to partially seal said chamber in the impeller, a throat on said impeller, a suction opening in said casing surrounding said throat and a re-
5 movable bushing interposed between said throat and said suction opening.

10. A centrifugal pump, comprising a casing, a self-balancing impeller provided with an annular extending flange forming a run-
ning joint with the suction, a shoulder on said flange and a removable inverted L-shaped

bushing secured in said joint adapted to form frictional engagements with said shoulder when the impeller moves downward.

In testimony that I claim the foregoing, I 15 have hereto set my hand this 11th day of July, 1913.

FERDINAND W. KROGH.
